UNITED STATES PATENT OFFICE.

JOHN RIDDELL, OF SCHENECTADY, NEW YORK, ASSIGNOR TO GENERAL ELECTRIC COMPANY, A CORPORATION OF NEW YORK.

BUCKET-CUTTING MACHINE.

1,006,280.

Specification of Letters Patent. Patented Oct. 17, 1911.

Application filed September 30, 1905. Serial No. 280,834.

To all whom it may concern:

Be it known that I, JOHN RIDDELL, a citizen of the United States, residing at Schenectady, in the county of Schenectady and 5 State of New York, have invented certain new and useful Improvements in Bucket-Cutting Machines, of which the following is a specification.

This invention relates to machines for 10 making buckets for elastic-fluid turbines, and especially to that class of machines which cut curved slots across the periphery of a disk, ring or a segment thereof, having radial vanes with curved faces upon which 15 the steam impinges in the completed turbine. These vanes, or buckets, may be of any suitable configuration, but in general their cross-section shows a body thick at the middle; that is, along the middle line of the periphery of the disk, ring or segment, with curved 20 tapering side walls which terminate in sharpened edges on opposite sides. The figure is approximately a lune, except that the outer curve runs into tangential portions at 25 the ends. The passages between the buckets have parallel walls, as a rule, and are substantially U-shaped with divergent ends.

The object of my invention is to provide 30 a machine which will cut these turbine buckets rapidly and accurately, and give them any curvature desired with only a few changes or adjustments of the working parts.

The machine is to some extent an improvement 35 upon the one disclosed in my pending application, Serial Number 163,320. As in that machine, the cutting tool is carried by a frame or cutter-bar which reciprocates vertically and rocks or swings laterally, its 40 path of resultant movement being determined by a stationary guide-arm. As in the former machine, means are provided for turning the tool to keep its cutting edge normal to the surface of the bucket. As in the 45 former machine also, the tool oscillates back and forth in a path of the desired curvature, cutting on the forward stroke and being slightly withdrawn by pneumatic devices on the back stroke, in order to avoid dragging 50 the edge of the tool over the work.

The several features of novelty will be hereinafter set forth and particularly pointed out in the claims.

In the accompanying drawings, Figure 1

is a perspective front view of a machine 55 embodying my invention; Fig. 2 is a perspective end view of the same; Fig. 3 is a longitudinal section of the working parts; Fig. 4 is a rear elevation of the machine; Fig. 5 is an elevation of the reciprocating 60 and swinging cutter-bar and its guide-cam; Fig. 6 is an elevation of the rocking sector gear and pinion; Fig. 7 is a longitudinal section of the tool-carrier; Fig. 8 is a front elevation of the tool-turning mechanism; 65 Fig. 9 is an end elevation of the same; Figs. 10 and 11 are end elevations thereof at opposite extreme positions; Figs. 12 and 13 show two forms of bucket which can be cut by this machine; Fig. 14 shows the guide-cam for 70 cutting the bucket shown in Fig. 13; Fig. 15 is a perspective view of the cutting tool; Fig. 16 shows one of the wearing-rings; Fig. 17 is a cross-section of the air-valve; Fig. 18 is a perspective view of the work-holder; 75 Fig. 19 shows some of the gearing; Fig. 20 is a longitudinal section of a tool carrier, showing a split tool and a split piston with the clamping bolts angularly shifted to bring them into view; Fig. 21 is a perspective view of said piston; Fig. 22 is a cross-section on the line 22—22, Fig. 20; Fig. 23 is an end view of a modification; and Figs. 24 to 31, inclusive, show another modification having tools which are advanced and 80 retracted alternately.

In order to obtain a clear understanding of the requirements of a bucket-cutting machine, reference should be made first to Fig. 12 which is an edge view of a portion of a 90 bucket wheel or segment thereof and shows an end view of one bucket. The curved face 1 is concentric with the center 2, while the face 3, from *a* to *b* is concentric with the center 4, the end portions 5 being tangents intersecting the face 1 at the sides of the wheel. The curved face 1' of the next bucket is concentric with the face 3, the space between them being the groove or slot cut by the tool 6. The cutting edge 7 of the 100 tool, which is shown in perspective in Fig. 15, is a straight line which coincides with a radius from the center 4, and extends from the face 3 to the face 1'. Devices hereinafter described maintain this position of the tool 105 relatively to the work at all points in its path. Between the points *a* *b* the path of the tool is circular concentric with the center

4. Beyond the points *a b*, its path is one of increased radius, being substantially a straight line. The machine must therefore provide for three movements; that is, it must feed the work up to the tool between successive cuts; it must carry the tool back and forth along a path of the proper curvature, and it must turn the tool in its carrier to keep its edge normal to the curve of the 10 bucket.

Referring now to Figs. 1 to 6, the frame of the machine will be observed to comprise a horizontal bed 8 supported at one end by the leg 9 and at the other by a box-like 15 pedestal, comprising a base 10, a body 10', and a top bracket 10''. On the bed is a longitudinally-movable saddle 11 on which are mounted two adjustable sliding heads, one of which 12, has a stout horizontal pivot- 20 stud 13, on which is pivoted the work-holder 14. In the edge of the work-holder, which is either a wheel or a segment, as may be required, are a number of equi-distant notches with which an index finger 15 can engage, 25 said finger being mounted on the index-head 16. A lever 17 enables the finger to be withdrawn when the work-holder is to be shifted to bring a fresh portion of the work in line with the bucket-cutting tool. 30 The distance between the two heads can be varied to suit the diameter of the bucket-wheel. Mounted on the head 16 is a clamp 150 adapted to engage the work-holder and hold the same against movement when the 35 cutting operation is taking place. The clamp is actuated by an eccentric on the spindle 151 and the latter is turned by an arm 152 and a rod 153 having a suitable handle thereon. The rod is guided by the 40 head 12. The rod is moved to the right to release the clamp and work-holder and to the left to secure them. The cutter-bar is mounted on the pedestal 10, and the saddle 11 can be fed up to it by a feed screw 18, 45 Fig. 4, meshing with a nut 19 on the saddle and driven by a gear 20 and a pinion 21. The short shaft 22 carrying said pinion is provided with a ratchet-wheel 23, engaged at regular intervals by a pawl 24, so that 50 the work is fed intermittently. The means for actuating the pawl forms a part of the mechanism now about to be described.

The machine is preferably driven by an electric motor 25 geared by pinion 26, Fig. 55 19, and gear 27 to a shaft on which is a loose spur-gear 28 which can be clutched to the shaft by a clutch 29 operated by a crank-handle 30, Fig. 1. A train of gears 31 communicates motion to a shaft 32, Fig. 3, to 60 which is secured a disk 33 provided with a diametrical slot in which slides a block carrying a crank-pin 34. The block can be adjusted in the slot by means of a screw 35 in order to vary the throw of the crank-pin.

A sector-gear 36 is pivoted on trunnions 37 65 at its lower end and has a longitudinal slot in which plays a sliding block 38 in which the crank-pin 34 is journaled. The slot is of sufficient length to allow the crank to revolve freely, and by its movement to impart 70 to the sector-gear a rocking motion. A sector-pinion 39 meshes with the sector-gear and gives motion to a rock-shaft 40, Fig. 2, on which it is secured. At a suitable point on said shaft is a rock-arm 41 which is connected by a link 42 with a lever 43 loosely mounted on the shaft 22 adjacent to the ratchet-wheel 23 and carrying the pawl 24. A hood or shield 44 partially covers the ratchet-wheel 23. It is provided with a hub 80 45 sleeved on the shaft 22 and carrying a worm-gear 46. A worm 47 meshes with said gear and is mounted on a shaft passing through the pedestal and having a handle 48, Fig. 1, moving over an index plate 49. 85 By turning said handle the hood is caused to cover or uncover certain teeth of the ratchet wheel, thus permitting the pawl, whose stroke is of a constant length, to engage with said wheel at different points in its stroke 90 and thereby vary the feed of the work. During the idle portion of its stroke, the pawl slips over the outer surface of the hood. It will thus be evident that the rocking of 95 the rock-shaft 40 is transmitted through the link to the lever and pawl, and thereby the ratchet-wheel, the shaft 22 and the feed-screw 18 are intermittently actuated to feed the work toward the tool during the return stroke of said tool. When the cut has been 100 finished, the work must be run back and shifted for a new cut. The reverse motion of the saddle is effected by means of a shaft 50, Figs. 2 and 4, connected by belt-pulleys and an endless belt 51 with the shaft 22 and 105 having preferably two gear-wheels running loose upon it. One of said gears 52 meshes with the spur-gear 27, while the other gear, 53, is driven in the opposite direction by an intermediate pinion 54 meshing with it and 110 with the gear 27. A clutch operated by the handle 55, Fig. 1, serves to connect either one of the gears 52, 53 with the shaft 50 when desired. When the work-feed is operating, the clutch is thrown off, so that the shaft 50 runs idle. But by clutching one of 115 said gears, the shafts 50 and 22 will be driven rapidly, and the saddle 11 can be run backward or forward as may be desired, moving one way when the gear 52 is clutched 120 and the other way when the gear 53 is clutched.

From the rock-shaft 40 is derived the movement of the tool-carrier, which consists essentially of an upright cutter-bar 56 125 mounted to slide vertically and laterally on that side of the pedestal facing the work-holder. The cutter-bar is slotted vertically

at its upper end to receive a bearing-block 57 adapted to slide in said slot and having a clamping plate 58 and bolts 59 by means of which it can be fastened at any point 5 along the slot. In the upper end of the pedestal is a vertical slot 60 in which slides a block 61 carrying a pivot-stud 62 which is journaled in the bearing-block 57. The lower end of the cutter-bar also has a vertical slot to receive a sliding-block 63 which is journaled on a wrist-pin 64 carried on the end of the rock-shaft 40. The oscillation of this shaft will thus swing the cutter-bar from side to side, pivoting on the stud 62. 10

15 In order to give the cutter-bar a reciprocating movement it has a pin 65 projecting laterally from its lower end and provided with an anti-friction roller which engages a curved slot formed by an arch-bar 66 and 20 a cam 67, both secured to a semi-circular swivel plate 68 resting in a semi-circular seat 69, concentric with the middle of the cam. The curved slot or guide-cam is highest at its middle, so that as the cutter-bar 25 is swung from one side to the other its roller rides up over the cam and down again on the other side imparting a vertical reciprocation to the cutter-bar simultaneously with its swinging movement. The swivel 30 plate 68 is angularly adjustable in its seat to permit the position of the cam to be varied in order to vary the shape of the bucket, as fully explained in my pending application aforesaid.

35 At about the middle of the cutter-bar 56 is a projecting boss 70, preferably circular in cross-section. The cutter-bar is somewhat thicker at this point and is faced off, both front and back, to slide smoothly between 40 the adjacent surface of the pedestal and and annular guide-plate 71 which is bolted to the pedestal. The opening in this plate and in the pedestal is large enough to permit the boss to have the most ample range 45 of movement of which the machine is capable. The guide-plate prevents the cutter-bar from twisting out of its proper plane, and relieves the stud 62 and the wrist-pin 64 from all bending strains due to any tendency 50 of the cutter-bar to twist under the stress of cutting.

The tool 6 is mounted in the boss 70 in perpendicular or substantially perpendicular relation to the plane of movement of 55 the rocking and reciprocating cutter-bar or frame. It has a flat shank which is inserted into a socket in a cylindrical holder 72, Fig. 7, which is held in the tapering and preferably split head of a collet 73 whose 60 tapering sides fit in a tapered recess in the end of a spindle 74. A key 75 engages with the holder, collet and spindle to prevent relative rotation of these parts. The shank of the collet extends centrally through the

spindle, its other end being screw-threaded 65 to receive a nut 76 which abuts against the spindle and serves to draw the collet into the tapering socket and compress its jaws upon the tool-holder. The spindle is cylindrical and is mounted in a cylindrical bearing bored out in the boss 70 and in a cylinder 77 which is bolted thereto on the other side of the frame 56 from the tool. A bushing or bearing 78, preferably of bronze, is placed around each end of the spindle, 75 and the ends of the boss and the cylinder are split at 79 to enable them to be drawn in tightly on the bushing by bolts passing through the holes 80. The bushings themselves are split to provide for taking up 80 wear. The spindle is thus rotatably mounted in the swinging and reciprocating cutter-bar, this capacity for rotation being afforded in order that the tool may be turned to keep its cutting edge normal to the curve 85 of the bucket. The turning movement is effected as follows, Figs. 7 to 11 inclusive: A radial arm or lever 81 is secured to the rear end of the spindle where it projects beyond the cylinder 77. On this lever is a 90 shoe 82 carrying a wrist-pin 83 which is journaled in the upper end of an eccentric-rod 84 whose lower end forms half of an eccentric strap 85 encircling an eccentric 95 secured to the rock-shaft 40. On the eccentric-rod is a shoe 87 in which is journaled a wrist-pin 88 which is carried by a block 89 slidably lengthwise in an undercut groove in one arm 90 of a bell-crank lever secured on a rock-shaft 91 which is journaled in the pedestal body 10'. By means of a wedge or gib 92 underlying said block 89 and a screw 93 engaging with said wedge, the block 100 can be securely locked at any point along the undercut groove in which it slides. The bell-crank lever has a second arm 94 connected by a link 95 with an arm 96 on the rock-shaft 40, said arm being preferably integral with the arm 41 which actuates the work feeding mechanism and forming therewith 105 a bell-crank lever. It will be seen that the oscillation of the upper bell-crank lever 90, 94, causes the eccentric-rod 84 to be swayed from one side to the other of the center line 110 c d of the two rock shafts, and that this 115 rocks the spindle 74 in its bearings. If the spindle-bearings were stationary, it would be sufficient to simply pivot the rod at its lower end but since the spindle itself travels back and forth in an arched path corresponding with the curve of the bucket, as shown by the dotted line e in Fig. 10, and since there is a tangential portion at each end of said curve, it becomes necessary to 120 draw down the rod lengthwise during the end portions of its stroke in lines parallel with the movement of the spindle and at the same speed, in order to check the angu-

lar motion of the spindle. The throw of the eccentric is calculated to accomplish this result, and it will be seen in Figs. 10 and 11 that the eccentric pulls the rod downward at the times that the spindle is traveling downward along the tangential portions of its path.

From Fig. 9 it will be seen that the spindle, the two wrist-pins, and the eccentric all 10 pass the center line *c d* at the same instant. The distance between the centers of the spindle and the wrist-pin on the eccentric-rod is quite small, so that the turning effect at this point is quite rapid; the tool moving here 15 along the central circular portion of its cut, a portion which is of small radius. The rapidity of angular movement is enhanced by the fact that the wrist-pin 88 is at this point of its travel nearest to the center of 20 the eccentric and therefore urging the rod over by a short leverage. This effect can be varied by adjusting the pin 88 along the groove in the lever arm, the rapidity of movement being increased the nearer said 25 pin is to the center of the eccentric. Such an adjustment also tends to shift the shoe 82 farther out on the radial spindle-lever 81 at each end of the stroke, and as this amounts virtually to lengthening the recip- 30 roating movement of the rod, it follows that the tangential portions of the bucket will be longer, which is just the result de- 35 sired when the central circular curve is made smaller. It will be understood that these 40 parts must all be carefully adjusted to cor- respond with the particular cam used for guiding the swinging and reciprocating cutter-bar, so that the tool will be turned in exact accordance with the curve determined 45 by said cam. It will also be noticed that the lower corner of the tool coincides with the center of the spindle so that the tool turns on this as an axis, and the cutting edge is kept truly radial at all times as it sweeps over the circular curve.

It now remains to describe the means for retracting the tool during the back stroke to prevent it from dragging or being choked by chips. On referring to Fig. 7 it will be 50 observed that the cylinder 77 is chambered or counterbored just back of the boss 70, and that the spindle 74 has a collar or piston 97 fitting said counterbore. A split spring packing ring 98 surrounds a reduced 55 portion of said piston, and at each end of said piston are packing-rings 99, adjacent to which are wearing-rings 100 of hardened steel, each having a series of internal grooves 101, Fig. 16. In the outer face of each ring 60 is a radial groove 102 registering with an air-admission duct 103 formed in the body of the cylinder and leading to ports 104 in the walls of a cylindrical valve-chest 105 formed in or secured to the cylinder 77. An 65 oscillating valve, preferably a hollow cylin-

der 106, having a supply port 107, two admission ports 108, and an exhaust cavity 109, controls the ports 104 and an exhaust port 110. A rocking stem 111 operates said valve being itself actuated by a lever 112 which is 70 struck on opposite sides alternately by tappets 113 on the hub of the radial spindle-lever 81. The tappets are angularly adjustable around said hub to permit an accurate timing of the parts. Packing-rings 114 surround the spindle adjacent to the wearing-rings. The compressed air enters the valve chest through a supply port 115 and passes freely to the interior of the hollow valve, from which it is admitted alternately, by the 75 oscillation of the valve, to the ducts 103. Passing under the wearing ring it forces the piston to the end of its stroke and thus moves the spindle lengthwise, either to force the tool up to the work and hold it in cutting 80 position, or else to withdraw it for the return stroke; the actuation of the valve occurring at the end of each stroke of the tool. The longitudinal movement of the spindle is so slight—not much over one one-hundredth of an inch—that no perceptible 85 shock is occasioned. It will be understood that when one air-duct is open to the supply, the other is open to the exhaust, so that the reciprocation of the spindle is maintained so 90 long as the valve operates.

The operation of the several mechanisms has been described above, but it is thought that a brief summary of the operation of the machine as a whole will assist in a clear understanding of it. The disk, ring or segment 100 in whose edge the buckets are to be cut is fastened to the work-holder 14, which is centered on the stud 13 on the head 12 and the latter is adjusted on the saddle 11 to the proper distance from the tool. The index-head 16 is then adjusted so that its index-finger 15 will engage the first notch in the work-holder. The motor is then started, and the cutter-bar 56 begins to swing and reciprocate, rising and falling as it passes back and forth over the cam 67. This causes the tool to pass across the edge of the work in a curved path corresponding with the curve of the bucket to be cut. By means of the bell-crank and the eccentric rod, the tool-spindle is rocked to and fro in its bearings to keep the cutting edge of the tool normal to the curve. As the peripheral speed of the sector-gear 36 is greater when the crank-pin 34 is 110 at the lower end of the slot in said gear than when it is at the upper end thereof, the cutting stroke of the tool is made to correspond with the slower movement of the gear, and the return or idle stroke with the faster movement thereof. At the beginning of each cutting stroke, a tappet 113 on the tool spindle oscillates the air-valve and compressed air is admitted behind the piston on 115 the spindle to advance the tool slightly. At 120 125 130

the beginning of the return stroke, air is similarly admitted in front of the piston to retract the tool and prevent dragging. During the return stroke, the work is fed toward the tool by the pawl 24 and ratchet 23 and the gearing connecting them with the feed-screw 18 acting on the saddle. When the bucket has been cut to the proper depth, the feed is reversed, the saddle run back, and the work-holder shifted a notch to bring a fresh portion of the work in line with the tool.

Figs. 20 to 31 show three modifications in which provision is made for two tools placed face to face, with means for advancing and retracting them alternately, so that one will cut on one stroke of the cutter-bar and the other will cut on the return stroke, thus doubling the rate of cutting without increasing the speed of the machine. In the construction illustrated in Figs. 20, 21 and 22 the spindle 116 is rotatably mounted in bearings 78 in the boss 70 and cylinder 77, and projects beyond said cylinder to receive the hub of the radial lever 81, just as in the former construction. But the spindle does not reciprocate, being prevented from doing so by a collar 117 which fits between packing-rings 118 in an annular recess in the boss 30 and the cylinder. The spindle is bored to receive two plungers, capable of independent longitudinal movement in parallel lines. If desired, they may be mounted in separate chambers as indicated in Fig. 23, but it is preferred to place them side by side in a single cylindrical bore, each plunger being a half-cylinder 119, as shown in Fig. 21. On each plunger is a piston-head 120 fitting a counterbored part of the spindle. Packing rings 121 are placed in the counterbore in front of and behind the piston; those in front being backed up by tapered glands 121' to make a tight joint. Air-ducts 122, 123 lead from the valve-chest 105 to points in front of and behind each piston, and the admission and exhaust of compressed air is governed by an oscillating valve 106, as in the other construction. It will be noticed that the duct 122 leads to the rear of one piston and the front of the other, while the duct 123 runs to the front of the first piston and the rear of the other. It follows that when air is admitted to duct 122 one piston is moved forward and the other backward, and that the reverse takes place when air is admitted to duct 123. Each plunger is bored longitudinally to receive a tool collet 124, secured by a nut 125 at its rear end and having a tapering head secured firmly by said nut in a tapered recess in the front end of the plunger. The adjacent sides of said heads are preferably in contact and are somewhat flattened, as shown in Fig. 21. In each head is a socket for a tool 126, the faces 127 of the tools sliding on each other as the

plungers move in and out. The parts are so arranged that at the end of each stroke of the cutter-bar, the tool that has been cutting is retracted and the other one advanced, so that on the return stroke this latter tool 70 will cut. The feeding mechanism is of course slightly modified so as to provide for an actuation of the feed-screw at the end of each stroke of the cutter-bar. By thus obtaining a cut on each stroke, it is evident 75 that the rate of cutting will be double that of the machine using a single tool. Figs. 24 to 31 illustrate another construction for carrying out this idea, in which the semi-cylindrical tool-carrying plungers 128 do 80 not have any pistons, but are provided in their adjacent flat faces with diagonal grooves 129 which cross each other obliquely when the two plungers are placed together. A blade 130 slides in registering transverse 85 grooves 131 and is provided on each side with a diagonal rib 132 fitting the adjacent diagonal groove 129. The blade passes down through a slot in the bottom of the spindle, and at its upper end is formed into a cylindrical rod 133 which has a sliding fit in a stuffing-box formed at the bottom of a cylinder 134 which is mounted on the spindle. The preferred construction of the cylinder and stuffing-box is that shown in Figs. 24 90 and 26. The cylinder has an integral top, and its open lower end is screwed into a flanged bottom 135 which has a counterbored neck screwing into a hole in the tubular spindle. A gland 136 in the counterbore 95 confines the packing 137, and is itself held in place by a thin annular plate 138 resting on the bottom 135 and clamped by the lower end of the cylinder. The rod 133 carries a piston 139 provided with packing-rings fitting the bore of the cylinder. Compressed-air is admitted above and below the piston through flexible hose 140 connecting with the valve-chest 105, which is the same as the one shown in Figs. 7 and 17. The 100 bracket 141, which is substituted for the cylinder 77 used in the other modifications, is open on top to accommodate the cylinder 134, and is cored out inside under the spindle to allow room for the projecting lower 105 end of the blade. In operation, the cylinder oscillates with the spindle, and at each end of its movement the valve is actuated by a tappet 113, in order that the air may cause the piston to move from one end of the 110 cylinder to the other. At each stroke of the piston and blade, the co-operating cam surfaces of the diagonal ribs and grooves cause the plungers to reciprocate, one moving in and the other out of the spindle, and this 115 change takes place after one of the tools has completed its cut, so that it is withdrawn, and the other tool is advanced to make the cut on the return movement of the cutter-bar. Fig. 25 shows the cylinder at one end 120

of its path of movement. The tappet has struck the valve-lever 112 and shifted the valve so that the piston has moved to the upper end of the cylinder and has retracted the uppermost plunger and advanced the lowermost one.

In accordance with the provisions of the patent statutes, I have described the principle of operation of my invention together with the apparatus which I now consider to represent the best embodiment thereof; but I desire to have it understood that the apparatus shown is only illustrative, and that the invention can be carried out by other means.

What I claim as new and desire to secure by Letters Patent of the United States, is,

1. In a bucket cutting machine, the combination of a pedestal, a cutter bar pivotally mounted thereon and guided to move in a given plane, a tool rotatably mounted in said bar, a power actuated rock-shaft having its axis perpendicular to said plane, mechanism connecting the rock-shaft and cutter bar for swinging the bar from side to side in said plane, a cam for moving the bar vertically in said plane as it swings, the cutting edge of the tool moving in a curved path which is the resultant of the action of the two movements, a device including a member mounted on said rock-shaft for turning the tool to maintain its cutting edge normal to the cut as it follows said path, a bed attached to the pedestal, a work-holder mounted on the bed, and means including a member carried by said rock-shaft for feeding the work-holder toward the cutter bar and tool.

2. In a bucket cutting machine, the combination of a pedestal, a driving shaft located in the lower part of the pedestal, a rock shaft mounted in the middle portion of the pedestal and geared to the driving shaft, a swinging and reciprocating cutter bar mounted and guided on the pedestal, a pivot about which the bar swings, a bed, a work holder mounted on the bed, and means for intermittently feeding the work holder in a line perpendicular to the plane in which the cutter bar moves.

3. In a bucket-cutting machine, the combination with a cutter-bar movable in a given plane, of a cutting tool mounted on the bar in perpendicular relation to said plane and having its cutting edge parallel to the plane, a rock-shaft for swinging the cutter-bar in said plane, a cam for reciprocating the bar in the same plane, the tool moving in a curved path which is the resultant of the swinging and reciprocating movements and is different from the curve of the cam, a work holder, mechanism for feeding the holder toward the tool which is intermittently actuated by the rock-shaft, and a driving shaft connected to the rock-shaft.

4. In a bucket-cutting machine, the combination with a cutter-bar movable in a given plane, of a rock-shaft for swinging the bar, means for actuating the rock-shaft, a cam for reciprocating the bar as it swings, a tool-spindle mounted on the cutter-bar which is movable about its axis, a tool mounted on the spindle which is perpendicular to said plane, and connections between the spindle and the rock-shaft for turning the spindle to keep the cutting edge of the tool normal to the cut.

5. In a bucket-cutting machine, the combination with a cutter-bar, of a rock-shaft for swinging the bar, means for reciprocating the bar as it swings, a rocking tool spindle mounted on the bar, and mechanism for rocking the spindle comprising an actuator on the shaft, a connection between the actuator and the spindle, and a bell-crank lever having one arm connected with said connection and the other arm connected with the rock shaft.

6. In a bucket-cutting machine, the combination with a cutter-bar, of a rock-shaft for swinging the bar, means for reciprocating the bar as it swings, a tool spindle mounted on the bar, and means for rocking the spindle about its axis comprising an arm on the shaft, a bell crank lever connected therewith, a pivot for the bell crank lever, an eccentric on the shaft, a connection between the eccentric and the spindle, and means actuated by the bell crank lever for varying the effect of the eccentric on the spindle.

7. In a bucket-cutting machine, the combination with a cutter-bar movable in a given plane, of means for imparting to the bar a combined swinging and reciprocating movement in said plane, a rocking tool spindle carried by the bar, a tool mounted on the spindle which is substantially perpendicular to said plane and has its cutting edge parallel to the plane, means for rocking the spindle about its axis during said combined movement to maintain said edge normal to the cut, and a device co-operating with said means for arresting the rocking motion of the spindle before the cutter-bar and tool have reached the end of the stroke.

8. In a bucket-cutting machine, the combination with a cutter-bar, of means for imparting to the bar a combined swinging and reciprocating movement, a rocking tool spindle carried by the bar, a lever on the spindle for rocking it, a swaying rod connected to the lever for actuating it, mechanism for swaying the rod, means for moving the rod longitudinally during the end portions of the stroke of the cutter-bar, a work-holder, and means for feeding the work-holder and the tool-spindle relatively to each other as the cutting progresses.

9. In a bucket-cutting machine, the com-

bination with a cutter-bar, of means for imparting to the bar a combined swinging and reciprocating movement, a rocking tool-spindle carried by the bar, a lever on said 5 spindle for rocking it, a swinging rod connected to the lever for actuating it, mechanism for swaying the rod, and an eccentric for moving the rod longitudinally, a work-holder, and means for feeding the work-holder and the spindle relatively to each 10 other as the cutting progresses.

10. In a bucket-cutting machine, the combination with a cutter-bar, of a rock-shaft for imparting to it a transverse movement, 15 means for reciprocating said bar, a rocking tool spindle carried by said bar and provided with a lever, an eccentric on said rock-shaft having an eccentric rod pivotally connected with said lever, and a lever connected with said rock-shaft and pivotally connected to the eccentric rod for swaying the 20 latter.

11. In a bucket-cutting machine, the combination with a rocking tool spindle, of 25 means for carrying it bodily in a path corresponding with the curve of the bucket, a lever on said spindle, a shoe sliding on said lever, a rod pivoted to said shoe, means for actuating the rod, a shoe sliding on said rod, 30 a lever pivoted to said last-mentioned shoe, and means for rocking said lever.

12. In a bucket-cutting machine, the combination with a rocking tool spindle, of 35 means for carrying it bodily in a path corresponding with the curve of the bucket, a lever on said spindle to hold the tool normal to the cut, a shoe sliding on said lever, a rod pivoted to said shoe, an eccentric for actuating said rod, a shoe sliding on said 40 rod, and a lever pivoted to said last-mentioned shoe.

13. In a bucket-cutting machine, the combination with a rocking tool spindle, of 45 means for carrying it in a path corresponding with the curve of the bucket, a lever on said spindle, a shoe sliding on said lever, a rod pivoted to said shoe, an eccentric for actuating said rod, a shoe sliding on said rod, a bell-crank lever, a wrist-pin adjustable along one arm of said bell-crank lever and journaled in said last-mentioned shoe, and means for actuating the bell crânk lever.

14. In a bucket-cutting machine, the combination with an oscillating tool spindle, of 55 a rock shaft, a bell-crank lever, means for carrying the spindle to and fro across the center line of the shaft and lever, in a path corresponding with the curve of the bucket, a lever on the spindle, a shoe sliding on said 60 lever, an eccentric on the rock-shaft having an eccentric rod pivoted to said shoe, a second shoe sliding on said rod and pivotally connected with said bell-crank lever, and actuating connections between said bell-crank and the rock-shaft.

15. In a bucket-cutting machine, the combination with a swinging and reciprocating cutter-bar, of a tool spindle carried thereby, means for giving said spindle angular movement, a piston for giving it longitudinal reciprocating movement, a rotary valve controlling the admission and exhaust of fluid-pressure for reciprocating said piston, and a lever on the valve-stem arranged to be actuated by the angular motion of the 75 spindle.

16. In a bucket cutting machine, the combination of a cutter bar having a single plane of movement perpendicular to that of the work, a means for positively swinging the 80 bar to cause the tools to enter the work on one side and leave on the other, a means for reciprocating the bar as the tools pass through the work, a work-holder, two cutting tools and holders mounted on the bar, 85 and means for advancing and retracting the tools and holders alternately.

17. In a bucket cutting machine, the combination of a cutter bar having a single plane of movement perpendicular to that of the 90 work, cutting tools mounted on the bar, a means for positively swinging the bar to cause the tools to enter the work on one side and leave on the other, a means for reciprocating the bar as the tools pass through the 95 work, a work-holder, and means actuated by fluid pressure for alternately advancing and retracting the tools.

18. In a bucket cutting machine, the combination of a cutter bar having a single plane 100 of movement perpendicular to that of the work, cutting tools, plungers carrying the tools which are mounted on the bar, a means for positively swinging the bar to cause the tools to enter the work on one side and leave 105 on the other, a means for reciprocating the bar as the tools pass through the work, a work-holder, and pneumatic means for reciprocating the plungers alternately.

19. In a bucket cutting machine, the combination of a cutter bar having a single plane of movement perpendicular to that of the work, a means for positively swinging the bar to cause the tools to enter the work on one side and leave on the other, a means for reciprocating the bar as the tools pass through the work, a work-holder, a spindle mounted in the bar for movement about an axis, two cutting tools carried by the spindle, and means for advancing and retracting the 115 tools alternately.

20. In a bucket cutting machine, the combination of a cutter bar having a single plane of movement perpendicular to that of the work, a means for positively swinging the 125 bar to cause the tools to enter the work on one side and leave on the other, a means for reciprocating the bar as the tools pass through the work, a work-holder, a spindle mounted in the bar, a means for oscillating 130

- the spindle to hold the tools normal to the cut, two cutting tools mounted in the spindle, and means actuated by fluid pressure for alternately advancing and retracting the 5 tools.
21. In a bucket cutting machine, the combination of a cutter bar having a single plane of movement perpendicular to that of the work, a means for swinging the bar to cause 10 the tools to enter the work on one side and leave on the other, a means for reciprocating the bar as the tools pass through the work, a work-holder, a spindle mounted in the bar, a means for oscillating the spindle to hold the 15 tools normal to the cut, two plungers mounted side by side in the spindle, a cutting tool in each plunger, and a fluid pressure means for reciprocating the plungers alternately.
22. In a bucket-cutting machine, the combination with a swinging and reciprocating cutter-bar, of a tubular spindle rotatable therein, two semi-cylindrical plungers fitting in said spindle, a valve controlling the 20 flow of fluid-pressure to actuate said plungers, and cutting tools carried by said plungers and working face to face.
23. In a bucket-cutting machine, the combination with a swinging and reciprocating cutter-bar; of a rotatable tubular spindle, 25 two semi-cylindrical plungers reciprocating in said spindle mounted on the cutter bar, a blade passing transversely between said plungers, coöperating cam surfaces on said blade and plungers, and means for reciprocating said blade.
24. In a bucket-cutting machine, the combination with a swinging and reciprocating cutter-bar, of a rotatable tubular spindle mounted on the cutter bar, two semi-cylindrical 30 plungers reciprocating in said spindle and having diagonal grooves in their meeting faces, a transverse blade having diagonal ribs engaging said grooves, and fluid-pressure means for reciprocating said blade.
- 40 25. In a bucket-cutting machine, the combination with a swinging and reciprocating cutter-bar, of a rotatable tubular spindle mounted on the cutter bar, two semi-cylindrical plungers reciprocating in said spindle and having diagonal grooves in their meeting faces, a transverse blade having diagonal ribs engaging said grooves, an air-cylinder 45 on said spindle, and a piston therein attached to said blade.
- 55 26. In a bucket-cutting machine, the combination with a swinging and reciprocating cutter-bar, of a bracket secured thereto and having a cut-away top, a tubular spindle journaled in said bar and bracket, semi-cylindrical tool-carrying plungers in said 60 spindle, an air-cylinder and piston mounted on said spindle in the cut-away portion of said bracket, and operative connections be-
- tween said piston and said plungers whereby they are alternately advanced. 65
27. In a bucket cutting machine, the combination of a pedestal having a base, a segmental gear pivoted to the base, means for oscillating the gear about its pivot, a rock shaft mounted in the pedestal above said gear, a gear on the shaft which meshes with the first gear, a pivot on the upper portion of the pedestal, a cutter bar having an elongated bearing slot at its upper end which engages said pivot, a connection between the 70 rock shaft and the lower portion of the bar for swinging it about said pivot, means for imparting a longitudinal reciprocating motion to the bar as it swings, guides on the pedestal for confining the movements of the 75 bar to a plane perpendicular to the axis of the rock shaft, a cutting tool carried by the bar, a work-holder, and means including a member mounted on the rock shaft for feeding the tool and holder relatively to each 80 other as the cutting progresses in a direction perpendicular to said plane.
28. In a bucket cutting machine, the combination of a work-holder, a pivoted cutter bar movable in a plane, a cutting tool carried by the bar and movable in said bar in a direction perpendicular to the plane, a rock-shaft for rocking the bar, a cam for reciprocating the bar as it rocks, the tool moving in a path which is the resultant of the 85 two movements, means driven by the rock-shaft for feeding the work-holder toward the tool as the cutting progresses in a direction at right angles to said plane, and means for moving the tool in the bar to 90 cause it to advance and recede at different portions of the path.
29. In a bucket cutting machine, the combination of a work-holder, a pivoted cutter bar movable in a given plane, a rock-shaft 95 for swinging the bar about its pivot, means for rocking the shaft, a cam for reciprocating the bar as it swings, a tool spindle rotatably mounted in the bar, means driven by the rock-shaft for feeding the work-holder toward the tool in a direction at right angles to said plane, means including an eccentric device actuated by the rock-shaft for turning the spindle to keep the 100 tool normal to the cut, a motor for advancing and receding the tool at different portions of the cutting movement, and means actuated by the spindle for controlling the 105 motor.
- In witness whereof, I have hereunto set 110 my hand this 29th day of September, 1905.
- JOHN RIDDELL.
- Witnesses:
- BENJAMIN B. HULL,
MARGARET E. WOOLLEY.
